UNITED STATES PATENT OFFICE.

ADOLPH M. HOLSTEIN, OF SYRACUSE, NEW YORK.

DESIGN FOR A CORNER-PIECE FOR COFFINS AND CASKETS.

46,830.

Specification for Design.

Patented Jan. 5, 1915.

Application filed September 11, 1914. Serial No. 861,316. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Corner-Piece for Coffins and Caskets, of which the following is a specification, reference being had to the accompanying drawing, forming a part hereof.

In the drawing, Figures 1, 2 and 3 are, respectively, side and front elevations and top plan view of my design for a corner piece for coffins and caskets.

This design of corner piece for coffins has the appearance of a shortened pillar with a base 1 of enlarged width, and with a covering 2 on the top having a tongue-like extension 3 hanging down along the central line of the pillar. The upper portion of the pillar is of rounding cross-section and the lower portion thereof is formed with angularly arranged faces extending upwardly

from the lower end of the pillar and merging into the outer surface thereof at a point between its ends. The angular faces are formed rounding in cross-section and are each provided at its lower portion with upper and lower rounding protuberances 4, 5, in line with the like protuberances on the other angular faces, so that said protuberances are arranged in two rows, one above the other.

I claim:

The ornamental design for a corner piece for coffins and caskets, substantially as shown and described.

In testimony whereof, I have hereunto signed my name in the presence of two attesting witnesses, at Syracuse, in the county of Onondaga, and State of New York, this 5th day of September, 1914.

ADOLPH M. HOLSTEIN.

Witnesses:

S. DAVIS,
F. B. PICKARD.
